UNITED STATES PATENT OFFICE.

EGBERT E. McCAMIS, OF GOWER, MISSOURI.

STIRRUP.

Application filed December 11, 1922. Serial No. 606,225.

To all whom it may concern:

Be it known that I, EGBERT E. McCAMIS, a citizen of the United States, residing at Gower, in the county of Clinton and State 5 of Missouri, have invented new and useful Improvements in Stirrups, of which the following is a specification.

An object of this invention is to produce a stirrup of a construction which will permit 10 a rider removing his foot therefrom, or rather having his foot automatically moved therefrom in the event of the rider becoming thrown by an unruly animal so that the rider will not be dragged on the ground by 15 the animal, and consequently injuries resulting from such incident effectively overcome.

To the attainment of the foregoing, and other objects which will present themselves as the nature of the invention is better understood, reference is to be had to the drawing which accompanies and which forms part of this application.

In the drawings:—

Figure 1 is a perspective view of the improved stirrup.

Figure 2 is an end view thereof.

Figure 3 is a side elevation, with parts broken away and parts in section.

The stirrup, in its entirety, is broadly indicated by the numeral 1, the same including 30 a foot rest or base 2 having an integral side 3 formed with a laterally extending eye 4 which projects over the foot or base portion 2 and is formed by bars as shown in 35 Figure 3 of the drawings.

The lower bar of the eye is indicated by the numeral 5 and the same is arranged at an upward and outward angle from the side 40 3 while the upper bar 5' extends at right angles thereto. For distinction, the outer reduced end wall of the eye is indicated by the numeral 6, the same having at its lower edge a centrally arranged notch 7.

By reference to the drawings it will be 45 seen that the foot or base portion 2 has its outer end terminating approximately in a line with the center of the eye and also that the said base is provided with a rounded socket 8 (Figure 3). In this socket there is received the cross sectionally rounded stem 15 which projects from the end of a base or foot extension 9. The stem 15 is provided with an annular depression 16, and there is passed transversely through the foot portion 2 a pin 17 that enters the said depression whereby the section 9 is held from longi-

tudinal movement with respect to the base 2, and also whereby the section 9 is permitted to revolve thereon.

The revoluble section 9 has its outer end 60 provided with an upwardly directed angle extension 18, the outer end of which being preferably bifurcated to receive therein a lug 10 secured by a pivot 11. The lug 10 is formed upon the lower end of the movable 65 side of the stirrup. The movable side is really in the nature of a gate, and will hereinafter be so referred to. The gate is indicated by the numeral 12 and has its free end centrally provided with a lug extension 13 70 to be received in the notch 7 and to be held therein through the medium of a spring 14 which is angle shape in formation as shown, the lower angle portion of which, indicated by the numeral 19, is secured by means 20 75 to the lower face of the revoluble base section 9, the opposite angle end resting against the outer face of the portion 18 and being also, of course, in contact with the outer face of the gate 12.

From the foregoing description, when 80 taken in connection with the drawing, it will be apparent that should a rider be thrown from his mount, his foot will be guided by contact with the bar 5 against the gate 12, swinging the gate to open position, and permitting the gate, with the element 85 9, to turn on the fixed base or foot portion 2 of the stirrup, thus releasing the foot of the rider from the stirrup and consequently 90 avoiding the rider being dragged on the ground by the animal thereby allowing him to escape injuries which would otherwise result from such event.

Having described the invention, I claim:— 95

A stirrup of the character described comprising a base including a foot rest having an integral side formed thereon and a socket at its other end, a right angle extending bar projecting from the upper end of the side 100 and being adapted to form the upper portion of an eye, an upwardly inclined bar extending from the side and forming the lower portion of the eye, an upstanding extension formed on the inclined bar and being provided with a socket in its lower end, a guide forming the opposite side of the stirrup and a portion of the bottom thereof respectively, 105 said guide including a pair of pivotally associated members, a lug projecting from the upper end of the upper pivoted member and being adapted to be received in the socket 110

of the upstanding extension, a rounded stem projecting from the free end of the lower pivoted member and provided at its end portion with an annular depression adapted to be received in the socket of the foot rest, a pin passing through the foot rest and received in the annular depression in the end

of the stem, and a spring secured to the last mentioned pivoted member and bearing against its companion member as and for the purpose specified. 10

In testimony whereof I affix my signature.

EGBERT E. McCAMIS.
